(57) CLAIM

The ornamental design for a prosthesis, as shown and described.

DESCRIPTION

The patent or application file contains at least one drawing executed in color. Copies of this patent or patent application publication with color drawing(s) will be provided by the Office upon request and payment of the necessary fee.

1. Prosthesis

1.1 : Front

1.2 : Three-quarter

1.3 : Side

1.4 : Back

1.5 : Top

1.6 : Top in perspective

1.7 : Bottom

The portions of the "prosthesis" shown by coloring form no part of the claimed design.

The broken lines in the drawing depict environmental subject matter only and form no part of the claimed design.
